[57] **CLAIM**

The ornamental design for a control unit for a combined automobile cassette player and radio, as shown and described.

DESCRIPTION

FIG. 1 is a front, top and left side perspective view of a control unit for a combined automobile cassette player and radio showing our new design;

FIG. 2 is a front elevational view; and

FIG. 3 is a right side elevational view.

The broken line structure forms no part of the claimed design and is included for illustrative purposes only. The rear of the control unit is conventional.
